UNITED STATES PATENT OFFICE.

DONALD H. YOST, OF YORK, PENNSYLVANIA, ASSIGNOR OF ONE-HALF TO FREDERICK R. YOST, OF YORK, PENNSYLVANIA.

INDUCTION-COIL.

No. 891,320.

Specification of Letters Patent.

Patented June 23, 1908.

Application filed October 23, 1907. Serial No. 398,785.

To all whom it may concern:

Be it known that I, DONALD H. YOST, a citizen of the United States, residing at York, in the county of York, State of Pennsylvania, have invented certain new and useful Improvements in Induction-Coils, of which the following is a specification.

My invention relates to an improvement in induction coils, and it has for its object to provide an improved construction and means of interrupting an electric current through the primary coil of an induction coil; and a further object consists in the provision of means for regulating the frequency of such interruptions.

A convenient embodiment of my invention is illustrated in the accompanying drawing forming a part of my specification, but it is to be understood that changes in the details of construction may be made without departing from my invention.

In the drawing,—

Figure 1 is a longitudinal central section of an induction coil embodying my invention; Figure 2 is a section on the line 2—2 of Figure 1, a portion of the interrupting mechanism being shown in dotted lines; and

Figure 3 is a sectional view of a portion of the device showing a modified construction.

30 Referring to the drawing,—

1 designates a primary coil of insulated wire, preferably of copper, and 2 designates a secondary coil of insulated wire, also preferably of copper. The primary coil is wound about a bobbin or support 3 of suitable insulating material. This bobbin is hollow and projecting into the same is a metallic core 5, preferably of soft iron, which is adapted to be magnetized and demagnetized by 35 the making and breaking of the electric circuit through the primary coil. This core may be a solid rod, as shown, or it may consist of a bundle of soft wires held together by suitable means.

40 The means for supporting and adjusting the core 5 longitudinally within the primary coil 1 will be described hereafter. The coils and the core are supported upon a suitable frame, the end portions 6 and 7 only of which are shown. It is deemed unnecessary to my invention to show and describe the side portions of the frame.

45 The devices for making and breaking the electric circuit are supported in a cup-shaped

device 8 of porcelain or other suitable insulating material, which is connected to the end 7 of the frame of the coil by means of metallic posts or rods 10 and 11, which are secured to the end 7 of the frame and the outer ends of which project through holes 15 in the bottom of the cup-shaped insulating device 8. The said device is held or secured upon the posts 10 and 11 by means of the nuts 16 which have screw-threaded engagement with the ends of the posts 10 and 11 which project beyond or below the bottom of the cup 8.

20 and 21 designate metallic plates or members connected to the bottom of the insulating cup 8 by means of screws 22. 25 designates a contact plate, preferably of 70 spring metal, which is secured to the plate or member 20, and which is in contact with the post 10. 26 designates a similar plate which is connected to the plate or member 21 and which is in contact with the post 11. The 75 plates or members 20 and 21 are separated from each other, as indicated most clearly in Figure 2 of the drawings. These plates or members 20 and 21 are preferably covered with platinum foil.

80 The primary coil 1 together with the core 5 of the induction coil, constitute an electro-magnet. The armature 30 for the said electro-magnet consists of a disk (preferably of soft iron covered with platinum foil). The 85 armature is provided with a central perforation 35, through which the pin or guide 36 projects. This pin or guide is connected to the bottom of the insulating cup 8 at a point 90 between the plates or members 20 and 21 and extends upwardly between the said plates or members as indicated in the drawings. The armature 30 is adapted to move freely longitudinally of the pin or guide 36 and along rectilinear lines.

95 It will be observed that one end of the primary coil of wire 1 is connected to a binding post 40, which in turn is connected by means of a wire 41 to one electrode of an electric battery (not shown). The other end 100 of the primary coil of wire is connected to the post 10. The post 11 is connected by means of a wire 45 to a binding post 46, which is connected by means of the wire 47 to the other electrode of the said electric battery.

105 When the armature 30 is in the position shown in Figure 1 of the drawings, it will be seen that the circuit through the primary

coil is complete and that a current may pass from the battery through the wire 41 into the primary coil, thence to the post 10, and the plate 20, through the armature 30 to the plate 21, and thence through the post 11 and the wire 45 to the wire 47 connected to the opposite electrode of the battery.

The passage of the current magnetizes the iron core 5, and movement of the armature 30 longitudinally of the pin 36 is occasioned so that the circuit is interrupted or broken. As soon as the circuit is interrupted, the armature 30 falls back into contact with the plates or disks 20 and 21, again completing the circuit. The operation may be repeated indefinitely.

It will be understood that upon the making and the breaking of the circuit through the primary coil, an induced current is produced in the secondary coil 2. The opposite ends of this coil are connected respectively to binding posts 50 and 51, which are in turn connected to wires 52 and 53, which may be extended to any point for the purpose of producing a spark or for any other purpose which may be desired.

It is desirable to provide means in a device of this character by the use of which the frequency of the interruptions of the current may be varied. To accomplish this purpose, I have conceived a construction in which the core of the electro-magnet is longitudinally adjustable so that it may move toward and from the armature 30 which operates to complete and break the circuit to interrupt the current of electricity.

It will be noted that the rod 36 projects into a perforation 55 in one end of the core 5, and that it serves as a guide to hold the core 30 in proper position relatively to the said interrupter or disk 30. The means for occasioning or effecting the longitudinal adjustment of the core 55 consists of a member 60 secured to the end 6 of the induction coil frame. The member 60 is provided with a screw-threaded opening 61. The core 5 projects through the said opening and is provided with a screw-threaded section 62, which is in engagement with the screw threads of the opening 61. The member 60 is provided with a circular flange 63, which is provided with teeth or indentations upon its edge, which are adapted to be engaged by teeth 64 upon a plate 65. This plate is provided with a central, angular opening 66 through which the end of the core 5 projects. The end portion of the core 5 is also angular, so that by turning the plate 65, the core is also turned, and by reason of its screw-threaded engagement with the stationary plate 60, longitudinal movement thereof is occasioned. The extent of longitudinal movement depends upon the extent of its revolution, and the extent of the latter movement may be measured by noting the space through which

the plate 65 is moved. If there are twenty-five teeth upon the plate 65, and a corresponding number of indentations in the upper edge of the flange 63, it will be understood that if the plate is moved through the space of one tooth, the core 5 will be turned one-twenty-fifth (1/25) of a revolution and will be moved longitudinally through a distance equal to one-twenty-fifth (1/25) of the pitch of the screw-thread.

The plate 65 is held so that the teeth thereon are in engagement with the indentations or teeth upon the flange of the member 60 by means of a wire spring 70, which is coiled about the projecting end of the core 5, one end of the said spring resting against the plate 65, and the other end resting against the lower or inner side of a nut 71 on the projecting end of the said core 5.

In the construction as described, the disk 30 rests upon the plates 20 and 21, by reason of gravity, and it is necessary, therefore, that in use the induction coil be held in a vertical or substantially vertical position.

In Figure 3, I have shown a slightly modified construction in which a wire spring 75 is coiled around the pin 36 and is located between the armature 30 and the adjacent end of the core 5 and acts to hold the said armature against the metallic members 20 and 21. If desired, this spring may be used at all times; but it is only necessary to use it when the coil is located in a horizontal position in which the action of gravity would not occasion the movement of the armature 30 upon the pin 36, in which case the spring must be relied on for this purpose.

In the construction shown, the cup 8 is readily removable so that the surfaces of the armature 30 and of the plates or similar members 20 and 21 may be readily and thoroughly cleansed.

Having thus described my invention, I claim:

1. An electric circuit having portions which are electrically disconnected from each other, whereby the said circuit is interrupted, an electro-magnet and the armature for the electro-magnet located between the said magnet and the said circuit and in contact with the disconnected portions of the circuit to complete the latter, and the said armature being adapted to oscillate between the said electro-magnet and the said circuit.

2. In a device of the character described, the combination of an electro-magnet, an electric circuit having an interruption therein, the armature for the said electro-magnet, the said armature being adapted to rest by gravity upon portions of the said circuit and bridge the said interruption and also to oscillate between the said circuit and the said electro-magnet.

3. In a device of the character described, the combination of an electro-magnet, an

- electric circuit having an interruption therein, a rectilinearly movable armature, means for occasioning the contact of the said armature with the said circuit, and the said armature being adapted to oscillate between the said circuit and the said electro-magnet.
4. In a device of the character described, the combination of an electro-magnet, an electric circuit, the armature of the said electro-magnet, the said armature being interposed between the said electro-magnet and the said circuit, and means for retaining the said armature in alinement with the said electro-magnet.
5. In a device of the character described, the combination of an electro-magnet, an electric circuit having an interruption therein, the armature of the said electro-magnet, the said armature being adapted to rest upon the said circuit and bridge the said interruption, and the said armature having a perforation therethrough, and a suitably supported guide extending through the said perforation to hold and guide the said conductor.
6. In a device of the character described, the combination of an electro-magnet having a movable core, means for occasioning movement of the said core, an electric circuit, and a movable member adapted to oscillate between the said electro-magnet and a portion of the said circuit, the frequency of oscillation of the said member being controlled by varying the distance between the core of the said electro-magnet and the said circuit.
7. In a device of the character described, the combination of an electro-magnet having a movable core, means for occasioning movement of the said core, an electric circuit, and the armature of the said magnet, the said armature being adapted to oscillate between the said core and a portion of the said circuit.
8. In a device of the character described, the combination of the core of an electro-magnet the said core having a perforation in one end thereof, means for occasioning longitudinal movement of the said core, and means extending into the said perforation to guide the said magnet to the position desired.
9. In a device of the character described, the combination of the core of an induction coil, the said core having a perforation at one end extending longitudinally thereof, means for occasioning longitudinal movement of the said core, a suitably supported pin extending into the said perforation, an electric circuit having an interruption therein, the said pin being located at the point of the said interruption, and a conductor movably mounted upon the said pin and adapted to oscillate be-
- tween the said electro-magnet and the said circuit.
10. An induction coil having a longitudinally movable core, means for occasioning movement of the said core, the said means comprising a stationary member with which the said core has screw-threaded engagement, and means for occasioning rotation of the said core, whereby longitudinal movement thereof is effected.
11. An induction coil having a longitudinally movable core, the said core having a projecting end portion the cross-sectional outline of which is angular, and means for occasioning movement of the said core, the said means comprising a stationary member with which the said core has screw-threaded connection, and the said member having a series of indentations, a movable member having a series of teeth in engagement with the said indentations, the said movable member having an angular opening through which the projecting end portion of the core extends, the sides of the said projecting angular portion being in contact with the sides of the said opening, whereby the turning of the said movable member occasions a turning movement of the said core.
12. In a device of the character described, the combination of an electro-magnet, an electric circuit having relatively stationarily supported disconnected portions, the armature of the said magnet located between the latter and the disconnected portions of the said circuit, and adapted to oscillate between the said circuit and the said magnet, and means for occasioning a change in the frequency of the said oscillations.
13. In a device of the character described, the combination of an electro-magnet, an electric circuit having disconnected portions whereby the said circuit is interrupted, the armature of the said electro-magnet adapted to contact with the said disconnected portions to bridge the said interruption, the said armature being adapted to oscillate between the said circuit and the said electro-magnet, and means for occasioning a movement of a portion of the said electro-magnet toward and from the said circuit, whereby the frequency of the said oscillations may be varied.
- In testimony that I claim the foregoing as my invention, I have hereunto signed my name this 19th day of October, A. D. 1907.
